UNITED STATES PATENT OFFICE

121,138

DESIGN FOR A DRESS ENSEMBLE

Alfred O. Gilbert, Chicago, Ill.

Application May 11, 1940, Serial No. 92,302

Term of patent 3½ years

To all whom it may concern:

Be it known that I, Alfred O. Gilbert, a citizen of the United States of America, residing in Chicago, county of Cook and State of Illinois, have invented a new, original, and ornamental Design for a Dress Ensemble, of which the following is a specification, reference being had to the accompanying drawing, forming part thereof:

Fig. 1 is a front view of a dress ensemble showing my new design.

Fig. 2 is a rear view thereof.

Fig. 3 is a fragmentary view of the front of the dress member of the ensemble.

Fig. 4 is a rear view thereof.

I claim:

The ornamental design for a dress ensemble, substantially as shown.

ALFRED O. GILBERT.
